LUMINAIRE

Giacinto C. D'Ercoli, Chicago, Ill., assignor to McGraw-
Edison Company, Milwaukee, Wis., a corporation of
Delaware

Filed Nov. 12, 1963, Ser. No. 77,363

Term of patent 14 years

(Cl. D48—31)

FIG. 1 is a side elevational view of a luminaire embodying the instant invention;

FIG. 2 is a top plan view of the luminaire shown in FIG. 1;

FIG. 3 is a bottom plan view of the luminaire shown in FIG. 1;

FIG. 4 is a view taken along lines 4—4 of FIG. 2;

FIG. 5 is a side elevational view of a modified form of the luminaire shown in FIG. 1;

FIG. 6 is a top plan view of the luminaire shown in FIG. 5;

FIG. 7 is a bottom plan view of the luminaire shown in FIG. 5.

The characteristic features of my design reside in the illustrated refractor and hood in combination with a conventional base.

I claim:

The ornamental design for a luminaire, as shown and described.
